Attorney

UNITED STATES PATENT OFFICE

JOHN SCHADE, OF HOLYOKE, MASSACHUSETTS, ASSIGNOR TO NATIONAL BLANK BOOK COMPANY, OF HOLYOKE, MASSACHUSETTS, A CORPORATION OF MASSACHUSETTS

LOOSE-LEAF BOOK

Application filed June 1, 1928. Serial No. 282,090.

This invention relates to loose leaf books, but has particular reference to books of this nature that have their side covers connected to some part of the structure by metal 5 hinges.

Heretofore the side covers have been secured to the book back structure by metal hinge elements, as is shown and described in patents issued to me as follows: No. 1,478,-
10 840, issued December 25, 1923, No. 1,508,820, issued September 16, 1924, No. 1,508,821, issued September 16, 1924, No. 1,512,488, issued October 21, 1924, No. 1,512,489, issued October 21, 1924, No. 1,540,228, issued June 15 2, 1925, No. 1,548,332, issued August 4, 1925, and No. 1,557,883, issued October 20, 1925.

In all the constructions shown in these 20 patents an intermediate metal back plate was employed which was hinged along its side edges to the inner edges of the side covers, and this back plate served as the bottom plate of the loose leaf mechanism, and said back plate was covered as a general practice with an outer back plate faced with 25 leather that corresponded in color and pattern with the color and pattern of the side covers.

It is the object of the present invention to 30 eliminate this intermediate metal back plate, by hinging the side covers directly to the cover plate of the loose leaf mechanism, so that the latter and the side covers shall constitute an entirely separate from the back of the book, and then to apply the book back 35 directly to the loose leaf structure, this back being either made of metal covered with leather, cloth or other material colored and patterned to give the desired artistic effect, or shaped from vulcanized fiber or other suitable 40 non-metallic substance, the back in either form carrying fastening devices for attaching same to the loose leaf structure.

The accompanying drawings illustrate 45 some of the ways in which the invention may be carried out, and in these drawings

Figure 1 is an inside view of a loose leaf book with the side covers opened and hinged to the cover plate.

Figure 2 is a rear view of the completed 50 book with the side covers opened.

Figure 3 is a view similar to Figure 2 with the back of the book removed.

Figure 4 is a detail perspective of the back of the book.

Figure 5 is a section at the line 5—5 of 55 Figure 1.

Figure 6 is a detail fragmentary elevation showing a modified way of forming the hinge eyes in the cover plate.

Figure 7 is a section at the line 7—7 of 60 Figure 6.

Figure 8 is a section at the line 8—8 of Figure 6.

Figure 9 is a view similar to Figure 1 but showing my invention as applied to a 65 form of loose leaf book in which boosters are employed.

Figure 10 is a rear view of the structure shown at Figure 9.

Figure 11 is a rear view of the book shown 70 at Figure 10 with the separate back removed.

Figure 12 is a fragmentary view of the cover plate as it appears prior to the formation of the hinge eyes at its edges.

Figure 13 is a plan view of the cover plate as it appears after a modified style of hinge eyes has been formed.

Figure 14 is a section at the line 14—14 of Figure 13.

Figure 15 is a cross section showing a slightly different way in which the cover plate could be formed with the hinge eyes from the construction shown at Figure 12.

Figure 16 is a sectional view showing still 85 another way in which the cover plate may be formed with the eyes from the structure shown at Figure 12, and

Figures 17 and 18 are respectively a fragmentary rear view of a modified form of 90 cover plate and a sectional view showing the side covers hinged to said plate.

Similar numerals of reference denote like parts in the several figures of the drawing.

Referring to Figures 1, 2, 3, 4, 5, and 12, 95 1 is the cover plate casing which is blanked out with spaced fingers 2 extending laterally from its side edges as shown at Figure 12, and the side edges of the cover plates 100

are bent downwardly and inwardly as shown at 3 to form the retaining abutments 4 for the plates 5 that are pivotally connected at their inner edges and that carry the loose leaf prong members 6.

- 5 After the side edges of the cover plate have been bent in the manner above described the fingers 2 are bent upwardly in contact with these flanges 3 and then formed 10 into eyes 7, this construction being quite advantageous in that the flanges 3 are of double thickness.

The form of loose leaf structure comprising the pivoted plates 5 and prongs 6, and 15 the operation of these plates within the cover plate casing are well known and are illustrated in many prior patents and no further detailed description of these parts will be entered into herein. All that is necessary is that the cover plate shall be so formed at its side edges that the side covers 8 may be hinged thereto, usually by means of eyes 9 carried in spaced relation by the inner edges of the covers and interengaged 25 with the eyes 7 and a pintle 10 passed through both sets of eyes, and to complete the book a separate back 11 preferably having long eyelets 12 extending from its inner face, is applied directly to the structure 30 shown at Figure 3, these eyelets passing freely through openings 13 formed in the plates 5 and perforations 14 in the cover plate, the ends of these eyelets being then spun over or set against the cover plate as 35 shown at 15.

This back 11 is preferably made of vulcanized fiber with the eyelets 12 or other analogous devices securely anchored at the bases within the substance of the fiber, and 40 the latter is colored and patterned to conform artistically to the color and pattern of the side covers.

This back may be made of bakelite with the eyelets anchored therein, or it may be 45 made of metal covered with cloth or leather, but in all instances the back is suitably shaped and conformed in color and pattern to agree artistically with the color and pattern of the side covers.

50 These hinge eyes along the side edges of the cover plate may be formed in many ways, some of which are illustrated herein and will now be referred to.

In Figure 6 hinge eyes 16 are lanced out 55 of the cover plate and after bending into the form of eyes have their free ends extending inwardly as shown at 17 to provide flanges similar to the flanges 3, as shown particularly at Figures 7 and 8.

60 Or the fingers shown in the construction at Figure 12 may be bent downwardly into the form of eyes 18 as shown at Figure 15, the extremities of these fingers extending inwardly below the cover plate so as to form 65 rests *a* for the plates 5.

Or these fingers after being bent to form the eyes 18 may extend downwardly as shown at Figure 14, to provide the flanges 3^a.

Or, the side edges of the cover plate inside the bases of the fingers may be bent 70 downwardly and inwardly to form the flanges as shown at 19 in Figure 16, and the fingers curled around upwardly to form the eyes 20.

Or, the edges of the cover plate may be 75 bent downwardly and inwardly to form the flanges 4, as at Figure 5, and spaced perforations 24 made in the terminals of said edges, the fingers 25 that form the eyes on the covers being inserted through these perforations and curled around to form eyes 26, as shown particularly at Figures 17 and 18, this manner of hinging being shown in my Patent No. 1,557,883, aforesaid.

It will therefore be readily understood 80 that the manner of forming these eyes at the side edges of the cover plate is immaterial, the gist of the invention in this respect resting in the broad idea of providing spaced hinge eyes at the sides of the cover 85 plate so that the side covers may be hinged directly thereto.

The advantages of the construction hereinbefore described are quite important, in 90 that the side covers have nothing whatever to do with the back and can be assembled on the cover plate in connection with the loose leaf mechanism, so that it is merely necessary to apply the back plate without any intermediate metal plate whatsoever.

This invention lends itself admirably to a 95 loose leaf structure in which boosters are used for the purpose of opening the prong members, and referring to Figures 9, 10, and 11, this will be apparent.

In Figure 11 the side covers and cover plate are extended beyond the lines of hinging, and the booster clips 21 embrace the free ends of the cover plate, while flaps 22 are extended from the side covers across the rear end portions of the cover plate and parts carried thereby, these flaps being secured together in any suitable manner as by metal clips 23, this construction of the side covers being shown and described in my patent 100 aforesaid No. 1,540,228.

A book constructed in this manner so that it appears when viewed in the rear as is shown at Figure 11, would be somewhat unsightly unless provided with a back such 105 as has been heretofore described, but when the back is applied the book will appear at the rear as is shown at Figure 10 and on the inside as is shown at Figure 9.

It is a fact that the constructions heretofore described would be just as serviceable 110 without a back as they would be with a back, although they would not have commercial value without the back, nevertheless, all the 115 mechanical functions and utilities of the 120

100

105

110

115

120

125

130

book would be present without the back, and this invention is therefore an innovation in that the side covers are hinged directly to the cover plate.

5 When the back is applied there is no metal plate intermediate between the back and the loose leaf mechanism, and the completed book is therefore both greatly simplified and lightened without detracting from its
10 strength appearance.

What is claimed is:—

The herein-described improvement in loose leaf books, comprising side covers, a metallic cover plate casing, prong carrying members housed within said casing, the sides of said casing having hinged connection with the inner edges of said covers, and a separate rigid back applied in the immediate rear of said members and secured to the cover casing.

20 In testimony whereof I affix my signature hereto.

JOHN SCHADE.
